UNITED STATES PATENT OFFICE.

SAMUEL E. HITT, OF ELYRIA, OHIO, AND JOSEPH I. PEYTON, OF JOHNSTOWN, PENNSYLVANIA.

INGOT-MOLD.

1,230,405.

Specification of Letters Patent. Patented June 19, 1917.

Application filed November 29, 1916. Serial No. 134,092.

To all whom it may concern:

Be it known that we, SAMUEL E. HITT and JOSEPH I. PEYTON, citizens of the United States, and residents, respectively, of Elyria, 5 in the county of Lorain and State of Ohio, and of Johnstown, in the county of Cambria and State of Pennsylvania, have invented certain new and useful Improvements in Ingot-Molds, of which the following is a specification.

This invention relates to improvements in ingot molds and is for the purpose of overcoming certain difficulties encountered in the manufacture of our previous inventions claimed in United States Patents Nos. 15 1,139,219 and 1,139,284, issued May 11th, 1915, Canadian Patents No. 162,723, issued May 25th, 1915, and No. 162,873, issued June 1st, 1915, and British Patent No. 20 12,047/15, (under international convention) date claimed, 22nd August, 1914.

In the ingot mold with vacuum chamber as previously designed, the inner wall becoming red hot and the outer wall remaining 25 comparatively cold, the difference of temperature is so great as to cause fissures in the casting, causing loss of vacuum, and it is therefore an object of this invention to provide an expansive outer wall for the 30 vacuum chamber to overcome this difficulty.

In our previous invention, some difficulty was encountered in molding the large heavy ingot molds with the vacuum chamber in the top walls, so it is a further object of our 35 present invention to make the upper portion of the ingot mold containing the vacuum chamber separate from the body of the mold.

A further object of our invention is to provide a covering for the top of the vacuum 40 head, to protect it from spill when the ingot is cast.

A further object of the present invention is to provide a better covering for the air exhausting valve.

45 In the accompanying drawings: Figure 1 is a central vertical section of the vacuum head, showing a portion of the ingot mold body. Fig. 2 is a half plan and half section on line α α of Fig. 1. Fig. 3 is a front view 50 of the vacuum head placed on the mold body ready for the cast.

Referring to the drawings, 1 indicates the mold body, 2 the upper portion of the mold or head, containing the vacuum chamber 3.

55 The joint 4, between the head 2 and the mold

1, may be planed true or left rough and filled with clay or other refractory packing. The joint 4 has no influence on the casting of the ingot in the mold, but facilitates casting of the head 2 and also makes it possible to 60 cast the head 2 in denser iron than the body 1 or in quite different material as cast steel.

The head 2 constitutes the top of the mold and consists of an annular hollow ring around the top of the ingot to be cast, and 65 has an inner wall 5, bottom 6, top 7, and outer wall 8, partly or wholly corrugated as at 9, to compensate for unequal expansion between the inner and outer walls. It is desirable to have the inner wall 5 as thin as 70 possible, so that it will come up to a red heat immediately when the assembled mold is poured full, but on the other hand, the inner wall 5 must be thick enough to withstand a number of casts. The outer wall 8 75 is necessarily thinner than the inner wall 5 on account of the corrugations 9, so that the top wall 7 is tapered to make a gradual transition between the inner and outer walls to avoid internal strains when cast. The 80 lower portion 10 of the outer wall 8 is tapered for the same reason.

Lugs 11 are for the purpose of keeping the head 2 central on the body 1.

The aperture 12 is provided with a pipe 14, 85 valve 15 and hose connection 16 for exhausting the air.

The top of the head 2 is provided with a cover 17 with central aperture 18 for pouring, when the mold is to be poured from the 90 top, and a shoulder 19 fitting loosely the inside of the mold to keep it in place.

The cover 17 is notched at 20 to hold in place the valve box base 21, which is secured to chamber bottom 6 by the stud bolt 22. 95 The cover 17 can thus move up and down with the expansion and contraction of the vacuum chamber, without breaking the valve box base 21.

The valve box 24 has a front 25, two sides 26 and bottom 27. The hood 28 and base 21 are made in one piece and form the top and back of the valve inclosure. The upper edges of the front 25 and sides 26 are tapered at 29 to fit a like taper of the hood 28. The bottom 27 carries a lug 30 and a tapered seat 31 for the key 32. The base 21 carries lugs 33 on either side of lug 30, for the purpose of seating the key 32. When the valve box 24 is swung into place, the key 32 holds the

- lug 30 against the base 21 and also drives the box 24 upon against the hood 28 until the tapered edges 29 fit snug. Lugs 34 are cast on the box 24 to facilitate handling.
- 5 The operation of our invention is as follows: Flexible hose is connected at 16 with an air pump or other means of exhausting the air; valve 15 is opened and chamber 3 is exhausted; valve 15 is closed, hose connection 10 removed, valve box 24 swung into position and secured with key 32. The assembled mold is now poured full of molten metal nearly to cover 17, the upper portion of the cast losing a small amount of heat to bring 15 the inner wall 5 up to a red heat. The effect of the vacuum to retain the heat in the head, keeping the upper portion of the cast molten to feed automatically any pipe or blow hole that had a tendency to form in the ingot 20 being cast, is the same as already described in our previous patents. The inner wall 5 coming to a read heat so quickly, expands considerably, while the outer wall 8 of the vacuum chamber 3 is still quite cold. The 25 corrugations 9 of the outer wall 8 will therefore stretch like a spring to compensate for the unequal expansion and will remain under tension as long as there is an appreciable difference in temperature between the inner 30 and outer walls. When the ingot solidifies and the ingot and mold cool off and become cold, the temperatures are again equalized and the corrugations 9 assume their normal shape. This spring effect of the outer wall 35 8 will relieve excessive strains and protect the walls of the chamber from cracking.
- Our present invention thus provides a 40 vacuum head capable of repeated use, making it more practical for general introduction and reducing the cost per ton of ingot cast over our previous inventions.

We have illustrated and described preferred constructions, but changes could be made within the spirit and scope of the invention.

We claim:

1. An ingot mold, a removable head therefor constituting a vacuum chamber, and hav-

ing means of compensating the difference of expansion and contraction between the inner 50 and outer walls of the said vacuum chamber.

2. An ingot mold, a removable head therefor constituting a vacuum chamber with corrugated outer wall, an aperture in said chamber and means of closure of the said 55 aperture.

3. An ingot mold, a removable head therefor constituting a vacuum chamber with corrugated outer wall, an aperture in said chamber, a valve closure for said aperture 60 and means for protecting the said valve.

4. An ingot mold, a removable head therefor constituting a vacuum chamber with corrugated outer wall, an aperture in said chamber, a valve closure for said aperture, 65 means for protecting the said valve and a cover for protecting the top of the said vacuum chamber.

5. An ingot mold, a removable head therefor constituting a vacuum chamber with corrugated outer wall, an aperture in said chamber, a valve closure for said aperture, 70 a hooded base 21 secured to the chamber bottom 6, a cover 17 for the vacuum chamber, the said base 21 arranged for vertical movement relatively to the said cover 17.

6. An ingot mold, a removable head therefor constituting a vacuum chamber 3 with corrugated outer wall 8, an aperture 12, pipe 80 14, a valve closure 15, a hooded base 21 secured to the chamber bottom 6, a cover 17 arranged to hold the base 21 in position and to allow for vertical movement of the said base relatively to the said cover, a valve box 85 24 arranged to fit the base 21 and hood 28 to inclose completely the valve 15, and means for holding the said valve box 24 in position.
